UNITED STATES PATENT OFFICE.

ROBERT S. BLAIR, OF SOUTH ORANGE, NEW JERSEY.

ADVERTISING APPARATUS.

1,171,019.

Specification of Letters Patent.

Patented Feb. 8, 1916.

Application filed July 9, 1909. Serial No. 506,643.

To all whom it may concern:

Be it known that I, ROBERT S. BLAIR, a citizen of the United States, residing at South Orange, in the county of Essex and State of New Jersey, have invented certain new and useful Improvements in Advertising Apparatus, of which the following is a full, clear, and exact description, such as will enable others skilled in the art to which it appertains to make and use the same.

This invention relates to advertising apparatus.

One of the objects thereof is to provide simple and practical apparatus of the best type peculiarly adapted for use in cars.

Another object is to provide efficient and reliable driving mechanism for advertising signs having moving parts.

Another object is to provide apparatus of the above nature, characterized by durable, compact and inexpensive construction, and quiet and efficient action.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing wherein is shown one of various possible embodiments of this invention, Figure 1 is a front elevation thereof. Fig. 2 is a sectional plan taken substantially on the line $x-x$ of Fig. 1. Fig. 3 is a detailed plan showing a guide. Fig. 4 is a sectional detail taken on the line $y-y$ of Fig. 3. Fig. 5 is a detailed plan of parts of a driving mechanism. Fig. 6 is a rear elevation of parts shown in Fig. 1. Fig. 7 is a sectional view taken on the line $z-z$ of Fig. 1. Fig. 8 is a detailed view of a portion of a card-holder. Fig. 9 is a sectional view of an entire card-holder taken substantially on the line $a-a$ of Fig. 8.

Similar reference characters refer to similar parts throughout several views of the drawings.

In order to render clearer certain features of this invention it may here be noted that in advertising apparatus and particularly apparatus of this nature for use in railway cars, the parts are exposed to sudden shocks, jarring and hard usage and yet should be compactly disposed as the available space is

limited. To achieve this reliability in action and compactness of arrangement without an undue crowding or complication of the parts is one of the aims of this invention. It may also be noted that in the use of advertising signs if it is sought to display a large number of advertisements to the passengers of a car by rapidly parading them past his field of vision there is a tendency to a confused impression which materially lessens the desired effect. With stationary apparatus, however, the number of signs within the convenient view of a passenger is less than might be effectively displayed. The provision of practical means whereby the advertising space of a car is increased without detracting from the effect produced by the individual signs is another of the dominant aims of this invention.

Referring to Fig. 1 of the drawings there is shown a frame comprising the upper strip 1 and the lower strip 2 suitably connected one with another and adapted to be mounted upon a car wall. Upon the lower side of strip 1 and the upper side of strip 2 are mounted a plurality of guides 3, the construction of one of which only will be described in detail as they are substantially identical in form.

Referring now more particularly to Figs. 3 and 4 the guide member 3 is formed of a metal angle piece having a portion of its horizontal flange 4 turned upwardly as at 5 to provide a channel 6. Upon the unturned portion 7 of the flange 4 is rigidly mounted a card-holder hereinafter described in detail, this member being secured in any desired manner between portions 7 of the upper and lower guides. There is thus provided a trough-like guide which is formed by the channel portion 6 and by the angle portion completed by the rear surface of the card-holder fixed thereon. Within the guides are slidably mounted movable card-holders 9, each of which is adapted to oscillate from a position at the rear of one of the fixed holders 8 to a position in front of another of said holders, this movement being permitted by reason of the inclined disposition of the guides as indicated at 10. The construction of these movable card-holders, which is substantially identical with that of the fixed card-holders, is indicated in Figs. 8 and 9 of the drawings, and comprises a sheet-metal plate 11 curved as at 12 and having its edges folded inwardly at 13.

and 14. Within the folds 13 is a rod 15 to stiffen the same and within the fold 14 is a movable rod 16 urged downwardly by a spring 17 to a position limited by the shoulder 18 formed upon the edge of the holder. An advertising card 19 is readily inserted in this holder by placing the same within the fold 13 upon the rod 15 and forcing its upper edge into the fold 14, any inequality in width being taken up by the rod 16. The card is then forced inwardly against the holder and is held firmly and smoothly in position by reason of the action of the spring 17. The movable holders 9 are formed of a length materially greater than that of the cards 19 whereby both edges of the card are exposed as indicated at 20, upon the movable holders being thrown outwardly, thus facilitating the insertion and removal of the cards.

Secured to the rear surface of each movable holder 9 is a lug 21, each of these lugs being connected to a rod 22 extending throughout the length of the apparatus.

Referring to Fig. 6 of the drawings there are shown downwardly extending abutments 23 and 24 formed upon or secured to the rod 22. These abutments are adapted to be engaged by a headed pin 25 upon a sprocket chain 26 passing over sprocket wheels 27 and 28 journaled upon the frame of the apparatus. The shaft of the sprocket wheel 27 is driven by a chain from a wheel 29 which is driven in turn through a suitable worm and worm wheel connection from a motor 30.

The abutments 23 and 24 are spaced preferably at a distance substantially equal to twice the length of travel of the moving signs and the distance between the outermost points of the sprocket chain 26 exceeds the distance between the inner surface of these abutments by a distance exactly equal to the desired travel of the signs.

The pin 25 is formed as shown in Fig. 5 in the drawings to permit outward and inward movement of the abutments 23 and 24 due to the inclined disposition of the signs 9 and there is provided a suitable guide 31 and an idle sprocket wheel 32 to direct the chain 26 and hold it in alignment.

The operation of the above described embodiment of this invention is substantially as follows: Assuming the parts to be positioned as indicated in Figs. 2 and 6 of the drawings and the chain 26 to be driven in the direction indicated by the arrows, the pin 25 will travel up to its point of engagement with the abutment 24 before the signs are moved. During the further travel of this pin to its passage about the sprocket wheel 28 the abutment 24 with rod 22 and all of the movable signs are moved to the position indicated in dotted lines in Fig. 6 of the drawings. From this point the pin 25 continues its travel with the lower part of

the chain without affecting the signs until it reaches the abutment 23 which now occupies the position indicated by the dotted lines. Further movement carries this abutment in a direction toward the motor to the position shown in full lines, thus again retracting all of the movable signs. By a proper spacing of abutments 23 and 24 and a proper length of chain 26 any desired time of movement or rest of the signs may be readily attained. 75

It will also be noted that the entire driving mechanism may be confined to a short space at one end of the sign even though the latter is of such length as to connect a large number of individual card-holders. Furthermore, the arrangement of parts is such that they will be uneffected by wear and cannot be thrown out of action even by severe jarring. This reciprocating movement of the rod 22 alternately throws the several 85 unitary movable signs 9 into a position in which they are all exposed, obscuring the corresponding fixed signs and into a position in which they are all obscured thus exposing the fixed signs. In this manner the 90 advertising space is doubled and the number of cards presented to the view of a passenger is correspondingly increased. Moreover, not only is the effectiveness of the advertisements not impaired but they are more 95 firmly impressed upon the beholder, due to their own movement and to their reiterated concealment and exposure.

It will be seen that there is thus provided an apparatus in which the several objects 100 of this invention are achieved and in which the above described and other advantages are attained.

The action is effective, the construction is cheap and reliable and the entire apparatus is well suited to meet the hardest practical use. 105

As many changes could be made in the above construction and many apparently widely different embodiments of this invention could be made without departing from the scope thereof, it is intended that all matter contained in the above description or shown in the accompanying drawings shall be interpreted as illustrative and not in a 110 limiting sense. 115

It is also to be understood that the language used in the following claims is intended to cover all of the generic and specific features of the invention herein described, and all statements of the scope of the invention which, as a matter of language, might be said to fall therebetween. 120

Having described my invention what I claim as new and desire to secure by Letters Patent is: 125

1. In apparatus of the nature described, in combination, a frame, a plurality of fixed unitary signs mounted in said frame in inclined positions, a plurality of movable uni- 130

5 tary signs, a plurality of pairs of upper and lower guides mounted in said frame, each guide extending in an inclined position from the front of one of said fixed signs to the rear of the neighboring sign and having mounted therein said movable signs, a member connected to each of said movable signs, and means adapted to reciprocate said member.

10 2. In apparatus of the nature described, in combination, a pair of fixed signs, a pair of guides extending forwardly of one of said signs and to the rear of the other thereof, a sign mounted within said guides and adapted to move from a position back of one of said fixed signs to a position forward of the other of said fixed signs, and means adapted to move said movable sign, each of said guides comprising a channel shaped 15 portion forwardly of one fixed sign and an angle portion at the rear of the other fixed sign.

20 3. In apparatus of the nature described, in combination, a frame, a plurality of fixed signs mounted in said frame, a plurality of movable unitary signs mounted in said frame in an inclined position, means adapted to guide said movable signs between said fixed signs into positions respectively in front of said fixed signs, and means adapted simultaneously to move said movable signs into and out of said positions, said guides being adapted to engage said movable signs 25 at their upper and lower edges.

30 35 4. In apparatus of the nature described, in combination, a frame, a plurality of fixed card holders mounted within said frame in inclined positions, guides mounted upon the upper and lower members of said frame and 40 extending from positions at the rear of said fixed card holders to positions forwardly thereof, a plurality of movable card holders

45 positioned in said guides, a member connected with said several movable card holders and provided with a pair of projecting portions, an endless chain mounted to travel in an upright plane and provided with a projecting member adapted alternately to engage said portions and reciprocate said movable signs throughout a distance substantially equal to their length, and means adapted to drive said chain.

50 5. In apparatus of the nature described, in combination, a horizontal support, a plurality of stationary sign holders disposed in different planes on said support, a plurality of sign holders disposed in different planes and movable on said support, guides extending in front and rear of the stationary sign holders, and means adapted to automatically 55 move the movable sign holders in the guides into and out of position opposite the stationary sign holders.

6. In apparatus of the nature described, in combination, a horizontal support, a curved 60 unitary sign fixed in said support in an inclined position, a curved unitary sign movable in said support, guides extending to the rear of said fixed sign and in front of a second fixed sign, said guides adapted to engage said movable sign at its upper and lower edges and guide the same from a position to the rear of said first fixed sign to a position in front of said second fixed sign, and means adapted to reciprocate said movable sign in said guides into and out of said 65 positions.

70 In testimony whereof I affix my signature, in the presence of two witnesses.

ROBERT S. BLAIR.
